(No Model.)

J. ROTCHILD.
PRESSURE REGULATOR.

No. 505,850.

Patented Oct. 3, 1893.

Attorney.

UNITED STATES PATENT OFFICE.

JOSEPH ROTCHILD, OF BROOKLYN, NEW YORK, ASSIGNOR OF THREE-FOURTHS TO GEORGE W. RENTON, ROBERT L. CRANFORD, AND GEORGE C. CRANFORD, OF SAME PLAGE.

PRESSURE-REGULATOR.

SPECIFICATION forming part of Letters Patent No. 505,850, dated October 3, 1893.

Application filed June 16, 1893. Serial No. 477,802. (No model.)

To all whom it may concern:

Be it known that I, JOSEPH ROTCHILD, of Brooklyn, county of Kings, and State of New York, have invented certain new and useful

5 Improvements in Pressure-Regulators, of which the following is a full, clear, and exact description, reference being had to the accompanying drawings, and to the letters of reference marked thereon.

10 My invention has relation to that class of devices or machines known as pressure regulators and employed to control the pressure of liquids or fluids which may flow through or past the devices, to prevent damage, to insure 15 uniformity of pressure, and for other valuable offices in connection with the medium operated upon.

Among the objects of my invention are the production of a machine of the class above 20 named, which shall be of few and simple parts capable of easy, accurate and certain operation by the action of the liquid or fluid,—to provide for easy adjustment of the valve to compensate for any wear after long use,—to 25 prevent the incoming pressure from tightening the valve in its seat,—to provide a single and ready means of regulating the pressure at which the liquid or fluid may be discharged and of changing this pressure at will,—and 30 to secure certain advantages and economies in the construction, operation and use of the machine, as will be herein first fully described and then pointed out in the claims.

In the drawings, Figure 1 is a side elevation 35 or exterior view of my improved pressure regulator. Fig. 2 is a vertical section and elevation upon a plane through line $x-x$ of Fig. 1. Fig. 3 is a horizontal section through the axis of the valve; and Fig. 4 is a cross 40 section through the valve and casing.

In all the figures, like letters of reference, wherever they occur, indicate corresponding parts.

A is the main shell (containing the valve) 45 and B the inlet and C the outlet openings for liquids or fluids at which any pipes or other vessels may be applied. Within shell A is a valve casing D of smaller diameter than said shell, leaving a free channel a between these 50 two parts, into which channel the liquid or

fluid is forced from the inlet. The casing D is very slightly conical on its interior and it is held in place against an abutment as b upon which it is crowded or packed by the end plug c which contains the outlet C.

55

E is a hollow, rotary valve, accurately ground into its casing or shell D, the valve and casing being correspondingly perforated on opposite sides, as at d and e . The valve is held in its seat against longitudinal movement by a screw bolt f passing through its closed end and entering a hollow internally and externally threaded plug g screwed in the end of casing D. The plug g is easily reached and turned through the inlet B, and it is set so as to bear against the end of the valve when the latter is properly seated. Then the valve is locked or held against the plug by bolt f , which is easily reached and turned through the outlet. When the valve after long use moves 60 loosely in its seat, the plug g may be turned back a trifle and the bolt f again tightened. The valve turns easily and smoothly on bolt f so as to avoid unnecessary friction at this part. The valve being slightly conical, largest 65 toward its delivery end, and being perforated on opposite sides, external pressure on the valve through ports e will be balanced, and this pressure instead of crowding the valve tighter in its seat, will tend rather to loosen 70 it, so that under all pressures the valve may be moved as easily as may be desired. Liquid or fluid under any pressure enters at the opening B, passes around casing D, through ports e and d (when they are opened), into 75 the inner cavity of the valve and out at the larger open end thereof.

To automatically turn the valve so as to arrest or check the flow of liquid or fluid, and to make this turning correspond with the 80 pressure produced by the outgoing medium, I connect the valve with a diaphragm which is exposed to and operated by the pressure of said medium.

Upon one side of shell A (and preferably 85 cast therewith as shown) is a cup shaped enlargement F, serving as a seat for a diaphragm G, the inner cavity H communicating with the interior of shell A through a suitable opening in advance of the position of the 90

100

ports through the valve and casing. The dia-phragm G is held in place by a bolted cap or cover H² and is supplied with a stem I extending above and below it and suitably set 5 cured by a ledge h and nut i. Around the upper part of stem I and within neck H' of cap H² is a spring K bearing upon nut i at one end against a regulating screw k at the other. The screw k is threaded into the upper 10 part of neck H', and by turning this screw the amount of pressure upon the upper side of the diaphragm can be regulated at will, as will be readily seen.

To connect the valve E with stem I, I employ a rod l which is threaded at one end into the material of the valve, passes through the opposite side of the valve and into a cylinder or block m which is seated in the lower end of stem I so that it can turn freely therein. 15 When the valve is moved longitudinally in its seat to loosen or tighten it, the rod l moves with it, and the block m being loosely mounted, will slide longitudinally in its seat to accommodate itself to the changed 20 position of the rod so as to avoid all cramping or binding and unnecessary friction. The rod l is adjusted to place by removing a plug n, which is afterward replaced. Under the construction explained, when the diaphragm rises or falls, the valve is rotated in 25 its seat through the medium of rod l and its connections. Suppose it be desired that the medium entering the regulator should leave it with one-half its initial pressure. The 30 spring K has then only to be adjusted so that the diaphragm will rise sufficiently to close the valve as soon as the pressure beneath it reaches the determined point.

The valve is normally open. So long as 35 the liquid or fluid on the outlet side of the regulator is considerably below the required degree it may continue to flow, but as soon as this pressure commences to increase the valve commences to close, and when the predetermined 40 pressure is reached the valve arrests all further flow and automatically opens upon any diminution of pressure. Any desired difference in degree of pressure between the

incoming and outgoing medium may be provided for by varying the tension of the spring. 50

The working parts of the valve being completely covered and the atmosphere excluded by the main shell, expansion and contraction of working parts are equal and they will therefore work easily and without sticking as would 55 otherwise occur.

The improved regulator is especially well adapted for use in connection with domestic and other plumbing, operating to arrest the flow of water from the main the instant the 60 pressure on the outlet side of the apparatus reaches a determined degree,—but it may be used in other situations as well.

Having now fully described my invention, what I claim as new, and desire to secure by 65 Letters Patent, is—

1. In a pressure regulator, the combination with the hollow valve and its casing located within the outer shell, of the hollow, threaded plug passing through the valve cage and the 70 screw bolt passing loosely through the valve and engaging the screw plug, the parts being arranged to adjust the valve to its seat within the valve casing and being accessible, the one from the exterior through the inlet port 75 and the other from the exterior through the outlet port, substantially as shown and described.

2. In a pressure regulator, the combination with the hollow, rotating valve and means for 80 adjusting it in its seat, of a rod secured thereto and extending at right angles to the axis thereof, the stem connected with the diaphragm and a block mounted and turning in the lower end of said stem and capable of 85 adjustment at right angles to the seat, the rod entering the block and serving to transmit motion from the diaphragm to the valve, substantially as shown and described.

In testimony that I claim the foregoing I 90 have hereunto set my hand in the presence of two witnesses.

JOSEPH ROTCHILD.

Witnesses:

W. J. MORGAN,
WORTH OSGOOD.
